UNITED STATES PATENT OFFICE.

FRED HARRIS DANIELS, OF WORCESTER, MASSACHUSETTS.

RAIL-BOND FOR ELECTRIC RAILWAYS.

SPECIFICATION forming part of Letters Patent No. 632,252, dated September 5, 1899.

Application filed June 27, 1899. Serial No. 722,042. (No model.)

To all whom it may concern:

Be it known that I, FRED HARRIS DANIELS, a citizen of the United States, and a resident of Worcester, in the county of Worcester and 5 State of Massachusetts, have invented a certain new and useful Improvement in Rail-Bonds for Electric Railways and other Purposes, of which the following is a specification.

The rail-bond in which my invention is 10 comprised is designed with more particular reference to its use on electric railways, and is of that type in which the bond proper or connector between the two terminals consists of strands of copper wire twisted together in 15 rope or cable form.

The object of the invention is to produce a bond in which the wire cable or rope is of so small diameter that with very little flattening it can readily go in between the rails and the 20 joint-plate or fish-plate which binds together the ends of adjoining rails, and, furthermore, to provide such a construction as will admit of expansion and contraction of the rail without disturbing the connections of the terminals 25 with the rails.

To this end I form the body of the bond of wire rope in such manner that the rope when united to the terminals will in effect form an endless loop, and I bring together the sides 30 of this loop at a point in their length between the two terminals, so as to form, in effect, a bond in which there are two eyes or openings which not only admit the free passage of the joint-bolts that secure the joint or fish plate 35 to the rails, but also amply allow for expansion and contraction of the rails.

The nature of my invention will be readily understood by reference to the accompanying drawings, in which—

40 Figure 1 is a side elevation, and Fig. 2 is an edge view, of one form of bond in partially-completed condition. Figs. 3 and 4 are corresponding views of the completed bond. Fig. 5 is a side elevation of the bond as applied to the meeting ends of two rails with the joint or fish plate removed. Fig. 6 is a cross-section of the same with the fish-plates in place. Fig. 7 is a side elevation, and Fig. 8 is an edge view, of a modified form of the 45 bond in incomplete condition. Figs. 9 and 10 are corresponding views of this modified form of bond in finished condition.

The bond in each instance is formed of two lengths *a* of wire rope of comparatively small diameter, which at their ends are united to 55 terminals *b*, so as to form, in effect, an endless loop with parallel or approximately parallel sides, which when the bond is in still unfinished condition are separated from one another by an interval practically throughout 60 their entire length, as seen in Figs. 1 and 7. The terminals *b* can be secured to the ends of the wire rope in any suitable manner—as, for example, they can be secured or welded thereto by pressure, so as to be substantially 65 integral therewith in the manner set forth in my Letters Patent No. 582,849, of May 18, 1897.

In the form of bond shown in Figs. 1 to 6 the sides of the loop of the wire rope are 70 brought together under pressure so as to lie side by side throughout their length except at the points where they remain spread apart to form the two edges or openings *c*. These eyes or spread-apart portions permit expansion and contraction of the rails without disturbing the connections of the terminals *b* with the rails, and they are also of sufficient dimensions to admit the free passage of the bolts *m*, Fig. 6, which bind the fish-plates *N* 80 and rails *R* together. After the terminals of the bond are secure to the meeting ends of the rails, as in Fig. 5, the fish-plates are applied and secured to the rails by bolts, as seen in Fig. 6, the bonds being between the 85 fish-plates and the rails. The small diameter of the wire rope of which the body of the bond is composed permits this to be done with very little flattening of the bond.

In the form of bond shown in Figs. 7 to 10 90 the two edges or openings *c* are formed by twisting the loop-shaped incomplete bond into what approximately resembles the figure 8, as will be readily understood by inspection of the figures referred to. The bond 95 after having been brought to the loop shape shown in Fig. 7 has its sides at or near the middle of their length brought together and then given a half-twist (or a turn of one hundred and eighty degrees) one on the other, 100 and are then subjected to pressure at their twisted meeting-point so as to flatten them and reduce the thickness of the bond at that point. To make the bond in this way the

terminals *b* in the incomplete bond must be so applied as to face in opposite directions, as seen in Figs. 7 and 8, so that when the loop is half-twisted, as in Figs. 9 and 10, the 5 terminals will, as seen in these figures, face in the same direction. This bond is applied to the meeting ends of the rails in the same way as illustrated in the drawings with reference to the other form of bond.

10 Having described my invention, what I claim herein as new, and desire to secure by Letters Patent, is—
A rail-bond having a wire-rope loop-like

body provided with terminals, the sides of the loop being brought together for a certain 15 portion of their length between the terminals and being separated from one another at other points to form openings or eyes, substantially as and for the purposes hereinbefore set forth.

20 In testimony whereof I have hereunto set my hand this 19th day of June, 1899.

FRED HARRIS DANIELS.
